UNITED STATES PATENT OFFICE.

ALEXANDER KONOFF, OF BROOKLYN, NEW YORK, ASSIGNOR TO VOICES INCORPORATED, OF WILMINGTON, DELAWARE, A CORPORATION OF DELAWARE.

SOUNDING DEVICE FOR DOLLS AND OTHER TOYS.

Application filed June 22, 1922. Serial No. 570,209.

The invention pertains more particularly to sounding or talking devices, so-called, for use in connection with dolls, and it resides in the novel sounding or talking device 5 hereinafter described and claimed, to be positioned within the body of a doll or other toy and which device will remain inactive when the doll is in one position and operate to emit a sound, as talking or crying, when 10 the doll is placed in another position.

One purpose of the invention is to provide a comparatively simple, durable, easily constructed and highly efficient sounding or talking device to be placed within the body 15 of a doll and which will, by preference, be capable of giving the well-known "ma-ma" or "pa-pa" sound when the doll is changed from one position to another.

The device of my invention comprises an 20 exterior box or casing, a tubular bellows located therein and secured at one end to one end thereof, a piston secured to the other or free end of the bellows and adapted of its own weight to collapse the bellows when 25 the casing is turned to one position and to elongate the bellows when the casing is turned to a reverse position, a central stationary shaft extending lengthwise of the casing and through the aforesaid piston and 30 serving as a guide therefor, a sound-box carried by said piston and having an aperture through which said shaft freely extends, and a reed secured in said head and opening into said sound-box, said shaft being recessed or 35 grooved annularly so that as the piston on the bellows is moving along said shaft and collapsing the bellows and driving the air therefrom through the reed, the outflow of air from the sound-box through said aperture 40 therein may be interrupted by those portions of the shaft at the sides of said annular grooves when said portions are respectively within said aperture and be free when the annular grooves in said shaft coincide, respectively, with the aperture in the 45 sound-box, this alternate interruption and release of the flow of air from the sound-box resulting in the reed efficiently giving 50 distinct sounds or intonations of the "ma-ma" or "pa-pa" character.

The invention will be fully understood from the detailed description hereinafter presented, reference being had to the accompanying drawings, in which:

Fig. 1 is a central vertical section through

a sounding device constructed in accordance with and embodying my invention, the device being shown in initial position preparatory to being operated on being reversed in position;

Fig. 2 is a like view of the same shown as having been reversed in position and the mechanism as having been operated;

Fig. 3 is a horizontal section through the same, taken on the dotted line 3—3 of Fig. 2;

Fig. 4 is a horizontal section through the same, taken on the dotted line 4—4 of Fig. 2, and

Fig. 5 is a perspective view of the same, a portion of the covering of cheese-cloth or 70 the like for the box or casing being shown as partly broken away.

In the drawings, 10 designates a cylindrical box or casing preferably formed of paste-board and having in its side walls 75 a series of horizontal rows of apertures 11. At the top and bottom of the box or casing 10 I provide reinforcing disks 12, 13, respectively, of indurated fibre or other reasonably stiff material, and exterior to said disks 12, 13 and serving to hold the same in position, I provide the box or casing 10 with caps 14, 15, which, with said disks, serve to close the ends of the box or casing 10. The disks 12, 13 add strength to the structure 80 and are centrally apertured to receive reduced end portions 16, 17 formed on a central stationary shaft 18 constituting one of the features of the sound producing mechanism and which becomes rigidly positioned 90 between the disks 12, 13, the ends of said shaft adjacent to the reduced portions 16, 17 thereof being in abutting relation to the facing sides of said disks, as shown in Figs. 1 and 2.

The shaft 18 is annularly recessed or grooved, as at 19, 20, the groove 20 being wider than the groove 19 and both of said grooves at their end portions being tapered or conical, as at 21. Aside from the annular grooves 19, 20, the shaft 18 is a plain cylindrical shaft and is divided by the annular grooves 19, 20 into an elongated end section 22, a less elongated opposite end section 23 and an intermediate section 24, the section 24 being between the annular grooves 19, 20.

Within one end of the box or casing 10 is secured a bellows 25, this bellows being of flexible material and in the form of a tube 110

or bag, one end of which is caught between the side flange of the cap 15 and the adjacent outer side surface of the box or casing 10, as indicated at 26, whereby the bellows 25 becomes at one end firmly secured in position. The opposite end of the bellows 25 is secured to a metal piston 27 which is in the form of a disk and extends across and rather snugly fills the transverse diameter of the 10 box or casing 10. The piston or head 27 is formed with an annular groove 28 and receives a wire ring around which the inner end of the bellows 25 is wrapped and whereby said end of the bellows becomes firmly 15 secured to the piston 27. In Fig. 1 I show the bellows 25 distended or elongated to its full extent by the pulling weight of the piston 27, while in Fig. 2 I illustrate the reverse position of the device and the bellows 20 25 as having collapsed under the pressing weight of said piston.

The piston 27 comprises a central sleeve portion 29 which fits, with reasonable clearance, the exterior portions of the shaft 18 25 and serves as an elongated guide for the piston 27 during its movements along said shaft. At its outer side the piston 27 is formed with a cylindrical flange 30 in whose outer end is rigidly seated a cap-disk 31 of 30 indurated fibre or other rigid material having a central opening 32 of slightly greater diameter than that of the shaft 18, upon which it moves. The flange 30 and cap 31 create a sounding chamber 33. At one side 35 of the sleeve 29 the piston 27 contains a boring 34 within which, by means of a holder 35, is secured a reed 36 of ordinary construction, said reed at one end opening into the chamber 33.

40 The box or casing 10 has applied upon its exterior surface a layer of cheese-cloth 37, for the purpose of preventing the entrance of dust or the like through the apertures 11 formed in said box or casing. The 45 cheese-cloth 37 is held in position and the caps 14, 15 are likewise secured in position by a coating of sealing wax or the like 38, applied over said caps and extending upon the adjacent edges of said cheese-cloth, as 50 illustrated in Figs. 1, 2 and 5.

The cap or disk 31 is formed with a venting opening 40.

When the box or casing with its enclosed mechanism is turned to the position shown 55 in Fig. 1, the weighted piston 27 slides downwardly upon the shaft 18 and stretches out or extends the bellows 25 so that at such time said bellows is of cylindrical form closely adjacent to the inner sides of the

60 box or casing 10. The movement of the weighted head or piston 27 to the position illustrated in Fig. 1 causes the disk 31 to slide downwardly upon the section 23 of the shaft 18 and the sleeve 29 of said head to 65 move downwardly upon the then upper end

of said shaft section 23 and over the annular groove 19 formed in said shaft, the section 24 of the shaft being within the sleeve 29 and the then upper end of said sleeve partly encompassing the annular groove 20 formed 70 in said shaft. When the head or piston 27 moves to the position shown in Fig. 1, the bellows or bag 25 becomes filled with air entering through the opening 40 and reed 36 and at times through the hole 32 and around the shaft 18. It is the expulsion of the air from the bellows or bag 25 through the reed 36 which causes said reed to give forth its sound, and this sound is modified by the movement of the piston 27 along the shaft 18, the expulsion of the air from the bellows or bag 25 and the sounding of the reed 36 taking place when the device is reversed so as to take the position shown in 75 Fig. 2. When the device is reversed in position so that the piston 27 is at the upper side 80 of the bellows or bag 25, said piston will slide down on the shaft 18 and collapse the bellows or bag 25, as shown in Fig. 2, and thereby force the air from within the bellows through the reed 36 and the opening 32 in the disk 31. The reed would make a prolonged sound in the absence of the annular grooves 19, 20 and shaft sections 23, 24, and in order to modify the sound of the reed 85 and cause it to produce the well-known "ma-ma" or "pa-pa" sounds, the weight 27 first carries the opening 32 of the disk 31 from over the shaft section 23, which substantially closes said opening, and over the 90 annular groove 19 which, not fitting the opening 32, permits the sound to escape through said opening. When, during the descent of the head 27, the opening 32 passes upon the shaft section 24, said opening 95 becomes substantially closed and said section 24 by choking said opening 32 effects a cessation of the sound of the reed. After the opening 32 in the disk 31, on the further descent of the head 27, passes from this shaft 100 section 24 and upon the annular groove 20, the opening 32 again becomes free for the passage of air from the bellows and the reed is permitted again to give forth or emit its 105 sound. The reed emits its sounds during the movement of the opening 32 in the disk 31 over the annular grooves 19, 20 in the shaft 18, the first sound, as "ma," taking place when the opening 32 leaves the shaft section 23 and passes over the annular 110 groove 19, and the second sound "ma," taking place upon the opening 32 of the disk 31 leaving the shaft section 24 and passing over the annular groove 20.

The sounds emitted by the reed 36 escape through the rows of perforations 11 in the box or casing 10, and I employ a considerable number of the openings 11 so that the sounds of the reed may freely escape, and as shown in Fig. 2, I have a row of 115 120 125 130

the openings 11 along the line of the annular groove 19 in the shaft 18 and another row of said openings along the line of the annular groove 20 in said shaft, this disposition of the openings 11 serving to facilitate the escape of the sounds of the reed from within the box or casing.

In the present instance the shaft 18 has two side recesses or grooves 19, 20, and I 10 make use of the two recesses or grooves for the purpose of securing two distinct spaced-apart sounds from the reed, as "ma-ma", on each operation of the device. If the shaft 18 should only have one side recess 15 or groove, as 19, the reed would only give one sound on each operation of the device, the duration of that sound depending on the width of the recess or groove. If the shaft 18 should be formed with three of the 20 side recesses or grooves, the reed would give three distinct sounds on each operation of the device, one sound being emitted as the opening 32 passes each of said side recesses or openings.

25 For a proper interpretation of certain of the claims forming part hereof it is understood that the bellows present may be correctly considered to comprise opposite head parts connected together by the flexible tubular member 25, one of the heads being the part 27 which is slidably supported by the shaft or post 18, and the other head being the bottom wall as 13 of the casing.

I have hereinbefore described the preferred embodiment of my invention but desire it to be understood that I do not confine the invention to all the details of form and construction shown and described since I am aware that many of these details may 40 be modified within the spirit and scope of my invention as defined in the appended claims.

What I claim as my invention and desire to secure by Letters-Patent, is:

45 1. A sounding device of the character described comprising an exterior box or casing, a stationary shaft mounted therein having near one end a side recess, an air-bag or bellows within said box or casing and secured at one end thereto, a piston to which the other end of said bag or bellows is secured and which is adapted by its weight, in one position of the device, to distend said bag or bellows and, in another position of the device, to collapse said bag or bellows for forcing the air therefrom and a reed carried by said piston, said piston having a sleeve portion to guide on said shaft and a sound-box into which said reed leads and 50 which has in its outer end an opening through which said shaft extends, said opening being substantially closed by the shaft except when passing over said recess and then being open to permit the flow of air 55 therethrough and the sounding of the reed.

2. A sounding device of the character described comprising an exterior box or casing, a stationary shaft mounted therein having a plurality of side recesses in one end portion thereof, an air-bag or bellows within said box or casing and secured at one end thereto, a piston to which the other end of said bag or bellows is secured and which is adapted by its weight, in one position of the device, to distend said bag or bellows 70 and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing in succession over said recesses and then 75 being open to permit the flow of the air therethrough and the reed to emit successive sounds.

3. A sounding device of the character described comprising an exterior box or casing, a stationary shaft mounted therein having a plurality of annular recesses in one end portion thereof, an air-bag or bellows within said box or casing and secured at one end thereto, a piston to which the other end of said bag or bellows is secured and which is adapted by its weight, in one position of the device, to distend said bag or bellows 90 and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing in succession over said recesses and then 95 being open to permit the flow of the air therethrough and the reed to emit successive sounds.

4. A sounding device of the character described comprising an exterior box or casing,

a stationary shaft mounted therein having a plurality of side recesses in one end portion thereof, an air-bag or bellows within said box or casing and secured at one end thereto, a piston to which the other end of said bag or bellows is secured and which is adapted by its weight, in one position of the device, to distend said bag or bellows and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing in succession 110 over said recesses and then being open to permit the flow of the air therethrough and the reed to emit successive sounds.

115 4. A sounding device of the character described comprising an exterior box or casing, a stationary shaft mounted therein having a plurality of side recesses in one end portion thereof, an air-bag or bellows within said box or casing and secured at one end thereto, a piston to which the other end of said bag or bellows is secured and which is adapted by its weight, in one position of the device, to distend said bag or bellows and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing in succession 120 over said recesses and then being open to permit the flow of the air therethrough and the reed to emit successive sounds.

125 4. A sounding device of the character described comprising an exterior box or casing, a stationary shaft mounted therein having a plurality of side recesses in one end portion thereof, an air-bag or bellows within said box or casing and secured at one end thereto, a piston to which the other end of said bag or bellows is secured and which is adapted by its weight, in one position of the device, to distend said bag or bellows and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing in succession 130 over said recesses and then being open to permit the flow of the air therethrough and the reed to emit successive sounds.

- over said recesses and then being open to permit the flow of the air therethrough and the reed to emit successive sounds, and said sound-box being formed by an encompassing flange projecting outwardly from and integral with the outer face of said piston and a cap secured on the outer end of said flange and having the aforesaid opening through which said shaft extends.
10. 5. A sounding device of the character described comprising an exterior box or casing, a stationary shaft mounted therein having near one end a side recess, an air-bag or bellows within said box or casing and secured at one end thereto, a piston to which the other end of said bag or bellows is secured and which is adapted by its weight, in one position of the device, to distend said bag or bellows and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing over said recess and then being open to permit the flow of air therethrough and the sounding of the reed, and said exterior box or casing having strong disks at its ends apertured to receive reduced end portions of said shaft and caps covering said disks and secured to the end portions of said box or casing.
6. A sounding device of the character described comprising an exterior box or casing, a stationary shaft mounted therein having near one end a side recess, an air-bag or bellows within said box or casing and secured at one end thereto, a piston to which the other end of said bag or bellows is secured and which is adapted by its weight, in one position of the device, to distend said bag or bellows and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing over said recess and then being open to permit the flow of air therethrough and the sounding of the reed, and said exterior box or casing having closing caps at its ends, perforated sides, a covering of cheese cloth over said sides and a sealing medium applied to said caps and the ends of said box or casing and serving to bind said caps and said covering in position.
7. A sounding device of the character described comprising an exterior box or casing, a stationary shaft mounted therein hav-

ing a plurality of annular recesses in one end portion thereof, an air-bag or bellows within said box or casing and secured at one end thereto, a piston to which the other end of said bag or bellows is secured and which is adapted by its weight, in one position of the device, to distend said bag or bellows and, in another position of the device, to collapse said bag or bellows for forcing the air therefrom and a reed carried by said piston, said piston having a sleeve portion to guide on said shaft and a sound-box into which said reed leads and which has in its outer end an opening through which said shaft extends, said opening being substantially closed by the shaft except when passing in succession over said recesses and then being open to permit the flow of the air therethrough and the reed to emit successive sounds, and said piston having at one side of its said sleeve portion a vertical hole extending through it to accord a housing for said reed, and said reed being positioned in said hole and at its outer end projecting into said sound-box.

8. A sound producing device comprising a casing having an air chamber therein and a weighty member movable by gravity within the casing to expel air from said chamber, a sound producing reed through which the air is expelled, and said weighty member having a sound receiving chamber provided with a wall having a sound emission opening therein, and relatively stationary means within the casing cooperating with said opening in the movement of said weighty member in one direction, said means having a tapering constriction in respect to the opening within the casing, to successively effect a gradual increase and a gradual decrease in the volume of sound emitted through said opening.

9. A sound producing device comprising a casing having an air chamber therein and a weighty member movable by gravity within the casing to expel air from said chamber, a sound producing reed through which the air is expelled, and said weighty member having a sound receiving chamber provided with a wall having a sound emission opening therein, and a post extending axially through the air chamber and through said emission opening and having longitudinally spaced parts successively cooperating with said opening in the movement of the weighty member in one direction, said post having constrictions between the spaced parts, to successively effect a gradual increase and a gradual decrease in the volume of sound emitted through said opening.

10. A sound producing device comprising a casing having an air chamber therein and a weighty member movable by gravity within the casing to expel air from said chamber, a sound producing reed through which the

air is expelled, and said weighty member having a sound receiving chamber provided with a wall having a sound emission opening therein, and an axially positioned post 5 extending through the air chamber and through said sound emission opening and supported upon the end walls of the casing, said post having longitudinally spaced parts cooperating with said opening in the movement of the weighty member in one direc-

tion, said post having tapering constrictions between said spaced parts, to produce at spaced intervals first a gradual increase and then a gradual decrease in the volume of sound emitted through said opening. 15

Signed at New York city, in the county of New York and State of New York, this 19th day of June, A. D. 1922.

ALEXANDER KONOFF.
